CLAIM

The ornamental design for a combined support and display bracket for self-contained breathing apparatus, as shown and described.

DESCRIPTION

FIG. 1 is a front perspective view of a combined support and display bracket for self-contained breathing apparatus embodying my new design;

FIG. 2 is a front elevational view thereof;

FIG. 3 is a side elevational view taken from the left of FIG. 1;

FIG. 4 is a top plan view thereof.
